DESIGN FOR A CIGARETTE LIGHTER

Alfred J. Flauder, Trumbull, Conn., assignor to Weidlich Bros. Manufacturing Company,
Bridgeport, Conn.

Application April 14, 1947, Serial No. 138,377

Term of patent 14 years

(Cl. D48—27)

To all whom it may concern:

Be it known that I, Alfred J. Flauder, a citizen of the United States and a resident of Trumbull, county of Fairfield, and State of Connecticut, have invented a new, original, and ornamental Design for a Cigarette Lighter, of which the following is a specification, reference being had to the accompanying drawing, forming a part thereof.

Fig. 1 is a top plan view of a cigarette lighter, showing my new design;

Fig. 2 is a side elevational view thereof;

Fig. 3 is a side elevational view of the cap thereof; and

Fig. 4 is a side elevational view thereof with the cap removed.

I claim:

The ornamental design for a cigarette lighter, substantially as shown.

ALFRED J. FLAUDER.
